TRIPODAL CANE

John deGignac, St. Charles, Ill., assignor to Tri-City Tripod Canes, Inc., St. Charles, Ill., a corporation of Illinois

Application October 14, 1954, Serial No. 32,674

Term of patent 3½ years

(Cl. D88—4)

Figure 1 is a rear view, in elevation, of the tripod cane showing my new design;

Figure 2 is a side view, in elevation, of the tripod cane as seen from the left;

Figure 3 is a horizontal cross-sectional view taken along the line 3—3 of Figure 1 and showing details of construction of the intermediate support for the legs of the cane; and

Figure 4 is a top plan view showing the contour of the top support element seen in Figures 1 and 2.

I claim:

The ornamental design for a tripod cane, as shown.
